CLAIM

[21] Appl. No.: 365,561

The ornamental design for a vent for mounting on window sill or frame, as shown and described.

[22] Filed: Jun. 14, 1989

DESCRIPTION

[30] Foreign Application Priority Data

Dec. 14, 1988 [GB] United Kingdom 1055687
[52] U.S. Cl. D23/388

[58] Field of Search D23/370, 371, 390, 391,
D23/392, 393, 387, 388; 98/37, 118, 99.8, 98;
52/302, 303

FIG. 1 is a front, top, and end perspective view of a
vent for mounting on window sill or frame, showing
our new design;

FIG. 2 is a front elevation view thereof;

FIG. 3 is a rear elevation view thereof; and

FIG. 4 is a cross-sectional view thereof, taken on the
line 4—4 in FIG. 2.

The vent for mounting on window sill or frame has
been broken away in the middle in FIGS. 1-3, to indicate
indeterminate length.
